ELECTRIC CONNECTOR

William H. Cook, Toledo, Ohio

Application December 18, 1945, Serial No. 635,800

6 Claims. (Cl. 173—361)

1

This invention relates to disconnectable association of electric conductors, usually in pairs, with other electric terminals or outlets, especially as encased in insulation housing as a general electrical fitting supply.

This invention has utility when incorporated with terminal pairs in a housing, wherein the lead-in conductor lines may be given a pinch action from relative rocking of an insulation member to bind the lines with the respective terminals in effective assembly for ready replacement.

Referring to the drawings:

Fig. 1 is a side elevation, with parts broken away of a two prong terminal connector, embodying features of the invention therein;

Fig. 2 is a view from the left, or prong projecting end of the connector of Fig. 1;

Fig. 3 is a side elevation of an angle projection or L-prong connector, a portion being broken away to show the terminal providing prongs;

Fig. 4 is a side elevation of the insulation rocker or conductor line pinch effecting plug which extends thru the connector of Fig. 3, between the terminal pair;

Fig. 5 is a fragmentary enlarged section thru the plug, on the line V—V, Fig. 4, showing the pinch effecting cam way for the conductor lines;

Fig. 6 is an elevation of the connector insulator section (Fig. 3) from which the prongs protrude, being the side central of the connector, with some portions broken away;

Fig. 7 is the facing inner side of the other insulator section to the showing in Fig. 6, being the one to the right in Fig. 3;

Fig. 8 is another L-prong connector, in which the rocker insulator for the line lock is in alignment with the entrance lines, instead of between the prongs as in Fig. 3;

Fig. 9 is a perspective view of the rocker insulator plug for the line locking with the terminals in the electric connector or fitting of Fig. 8;

Fig. 10 is an inside view in elevation of the left or prong projection side insulator section of the connector of Fig. 8;

Fig. 11 is the facing or opposite insulator section inside view in elevation, being the section at the right in Fig. 8; and

Fig. 12 is a view, partially in section and broken away, of a socket or prong receiver connector having the rocker to pinch the conductor lead lines to the terminals therein.

Figs. 1, 2

Electric conductor conduit 1 has branches 2 from which electric conductor wire strands 3, as

2

cleaned, may be thrust into a throat 4. The branches 2, are directed by a wedge or bridge 5 to have the wire strands 3 pass thru a port 6 and an eye opening 7 in a short right angle offset 8 from a terminal 9 extending along an insulation way 10. The ways 10 are diametrically disposed as outward from concentric tubular portion 11 of a tubular main insulation body 12 of the connector or fitting. At an end 13 of the body 12 remote from the throat 4, the terminals 9 have inward offsets to provide shoulders 14, outward from which prong portions 15 extend.

In assembly, between the offsets 8 and the shoulders 14, a plug 16 is thrust into the tubular portion 11 to shift the terminals 9 along the ways 10 to bring the openings 7 into aligned proximity to the ports 6. In this straight thrust placement of the plug 16, a lug 17 enters a recess 18 to a stop position to an arc way 19 therefrom, positively holding the plug against longitudinal further movement as to the body 12, when the lug 17 is away from the entrance recess 18.

A transverse depression, like a screw head, provides a seat 20 in the exposed central end of the plug 16 centrally of the end 13 of the body 12. By placing a coin or screw driver in the seat 20, and giving a rocking relative movement for the plug 16 as to the body 12, the respective cam or wedge faces 21 bounding the end of the plug 16, ride under the shoulders 14, thus tending to pull the offsets 8 away from the ports 6 to rub more closely to plane end 22 of the plug 16. From this end 22, extend insulation ways 23 in the insulation plug 16. These ways 23, at the entrance assembly position when the lug 17 enters the recess 18, are in alignment with the ports 6 and the openings 7. Accordingly, the thrust of the wire strands 3 thru the ports 6 extends such into the ways 23. The wedging-rocking action of the plug 16, now swings these strands for a conductor wire lead-in binding and pinching holding action. As the offset 8 is drawn relatively toward the plug face 22, while the ways 23 move away from alignment with the openings 7, the wire strands are firmly gripped into an effective electric conductor connection between the wires 3 and the terminals having the prongs 15.

To disconnect, there may not be current carrying connection for such operation. Access to the rockable plug 16 and its operating seat 20 may not be had until the prongs 15 are removed from the electric current supply outlet, or other electrical connection. A slight counterclockwise turning of the plug 16, is sufficient to free

the wire strands 3, so that they may be withdrawn by pulling on the conduit 1. Accordingly the fixture or fitting unit, without the requirement of any special tools, is in readiness for the one using the connector, to have terminally cleaned wire strands, spread and inserted thru the throat 4, one branch each side of the wedge 5 for the strands 3 to pass thru the ports 6, and aligned openings 7 on into the ways 23 in the insulation plug 16. With a coin, a slight clockwise turn serves simultaneously to lock effectively both sets of wire strands.

Figs. 3, 4, 5, 6, 7

An angle or L-connector (Fig. 3) is shown comprising an insulation section 24 from which prongs 25 project as nested in seats 26 about cylindrical opening 27 having an enlarged diameter region 28 from the face of the section 24 from which the prongs 25 protrude. A half throat 29 to a semicylindrical way 30 extends from an end 31 of the section 24.

A complementary insulation section 32, forming the back or outer portion of the installed unit, has a semi-throat 33 to a semicylindrical section 34, adapted for register with the throat portion 29 and way portion 30 to have an opening 35 in the section 32 align with the opening 27 in the section 24 and seats 36 register with the seats 26, for key ears seats 37. The prongs 25 have small offsets 38 which enter the seats 37 to retain the terminals 25 in the assembled unit as the sections 24, 32 are assembled by a rocker plug 39 thrust thru the openings 27, 35. A shallow groove portion 40 of the plug 39 is thru the outer or back side of the section 32, for a spring split locking ring 41 to snap therein and retain the unit assembled.

A wedge or spreader 43 in the way 34 locates a pair of ports 44 in alignment with ways 45 at the opposite side of the opening 35. When the plug 39 is thrust into the assembly with a turn seat 46 in mid position of the direction of the way 30, cam arc seats 47 provide way clearance from the ports 44 to the ways 45. The insert position of the plug 39 to the stop provided by the split ring 41, is to bring a lug 48 on the plug 39 into enlarged diameter or seat 28 of the section 24. The plug 39 is thus locked against axial shifting, but is free to be rotated by a screw driver or coin in the seat 46, thereby pinching the wire strands 3 in the arc or cam grooves 47 against the terminals 25 in the seats 36.

The rocking of the terminal holding plug 39 may not be effected until the fixture unit is withdrawn as to its prongs 25, say from an outlet or other fitting. As so cleared of electric current, the wedge control may be given a counterclockwise release twist for the wire strands, in the event clockwise turn used to effect the holding.

It is to be noted that the way 30 does not run into the opening 27, of the insulation section 24 (Fig. 6), but terminates in deflector means 42 for directing the inserted wire strands 3 as spread by the wedge 43 to enter the ports 44. Thus, as the reject wire strands are withdrawn, the replacement strands are readily inserted, and by a rocking in either direction, the cam way portions 47 effect strand pinching firmly to lock for the wires to be conductively snug with the respective terminals 25. The L-connector 25, 24, 32, with its prongs 25 to be thrust directly into, say a wall fixture or outlet box, may have the lead conduit 1, take off in parallelism with such wall.

Figs. 8, 9, 10, 11

Instead of the insulation rocker plug having its axial line parallel to and between the prongs (Fig. 3), an angle connector is provided with a rocker 49 (Fig. 9) seated between insulation sections 50, 51 (Fig. 8) taking the axial line of the lead-in wires thereto. The section 50 has a pair of horns or prongs 52 from an end 53 to a central semi-cylindrical seat 54. From the opposite end 55 of the section 50, a half channel way 56 extends to a spreader wedge 57 for two port sections 58 to align with openings 59 in angle or flange portion 60 of terminal prongs 61 seated in recesses 62 of the seat 54.

The complementary section 51 to the section 50, has a flush cross portion 63 as to its face to abut the section 50, which cross portion closes in the end of a semi-cylindrical seat 64, to locate the rocker plug 49, between the horns 52 and into the seat 54, for the terminals 61 as protruding thru the recesses 62 in extending out from face 65 of the section 50. The section 51, in register with the recesses 62, has seat portions 66 for the inner end portions of the terminals 61. A screw 67 thru an opening 68 in the section 50 enters an internally threaded opening 69 in the section 51. From an end 70, the section 51 has a way 56, to a wedge 57 and ports 58, complementary to the section 50.

With the rocker plug 49 between the prongs 52 and held against axial shifting by the end portion 63, the member 49 is retained in the seats 64, 54, by the insulation housing assembly screw 67. At this seated position, notch or seat 71 as medially approximating a common plane with the direction of the screw 67, the plug 49 has tubular ways 72 in alignment with the ports 58 and the openings 59 in the terminals. Accordingly, at this initial position it is in order for the one desiring to effect a conductor line assembly therewith, to shove wire strands 3 thru the way 56, to be spread by the wedge 57 for the strands from the separate branches 2, to be thrust thru the ports 58, the openings 59 to enter the ways 72. Now it is in order for the one using the connector, to place a coin or screw driver in the notch 71 and thereby rock the plug 49 either clockwise, or counterclockwise. In this rocking, the ways 72 are moved out of alignment with the openings 59, thereby pinching the wire strands 3 into a locked and firmly holding electric contact maintaining assembly with each of the terminals 61 at the single operation. Inasmuch as this operating notch or seat 71 is not readily accessible for line connection or disconnection, except as the connector has its prongs 61 away from electric current carrying source, there is a resultant automatic safeguarding for the operator against electric shock in any wiring connection, or for the converse, of disconnection, in the normal use of this device.

Fig. 12

Complementary insulation housing sections 73, 74 may be assembled by adhesive 75, after socket terminals 76 are placed in ways 77 therefor. Inwardly from offsets 8 of the terminals 76, at this assembly, a rockable plug 78 having integral therewith a stem 79 and head 80, is also in this housing unit. From an end 81 of the insulation housing, prong insert receiving ports 82 are in register for electric fixture prongs to be inserted therethru for conductor connection with the terminals 76.

Remote from the end 81, the housing 73, 74,

has a flare throat 83 to a spreader or wedge 84 to ports 85 in register with openings 7 in offsets 8 from the respective terminals 76. The head 80 has a coin seat or screw driver receiving notch 86, which, as directly crosswise to the common line connecting the prong ports 82, locates tubular ways 87 of the plug 78 in alignment with the openings 7. Accordingly, as conductor wire branches 2 have their cleaned frayed wire strands 3 thrust into the throat 83, the branches 2 may be spread by the wedge 84 and the wire strands 3 pass thru the ports 85, the terminal openings 7, and into the ways 87 of the insulation plug 78. Shoulders 88 on the terminals 76 oppose the offsets 8 and ride against end cam or wedge faces 89 of the plug 78. Upon placing a coin or screw driver in the seat 86, and giving thereto a clockwise turn from the end 81, the entire plug 78, with its stem 79 and head 80 integral therewith, travel further into the housing, as the ways 87 are thus placed out of register or alignment with the openings 7 in the terminals. There is a combined pinching from the axial shifting of the plug, for the strands 3, as well as the additional pinching in the out-of-alignment operation. There follows a positive holding of the wire strands from each of the branches, for effective electric current transmission in the lines thru the connector. Inasmuch as the conductor wire assembly requires access to the housing end 81, the terminals 76, must thereby be out-of-circuit relation with any fitting to be connected therewith. No special tools are required to disconnect or replace lead wires to this connector. A counterclockwise twist by a coin in the seat 86, releases the strands 3 for withdrawal from the housing 78, 74. Other or desired reconnection of wires is had by directing properly bare wire strands thru the throat 83, for passing by way of the ports 85, the openings 7, and into the ways 87, for clockwise turning of the plug 78 to simultaneously relock both lines of the branches therewith.

While the region of the rocker plug 16 has a major outer plane end 22, centrally there is a recess 90 into which may extend a centralizing projection 91 from the after side of the wedge 5. The key lug 17 in the arc way 19 as to the positive holding of assembly is against longitudinally moving the plug 16 for separation clear of the insulation housing 12. However, in such axial direction of the plug 16, there is sufficient clearance for the lug 17 in the way 19, to have the plug rocking effect an adequate locking operation, should the terminals not move, and the cams 21 promote movement of the plug axially in the housing 12. Actually the total movement of the offset 8 toward the plug end 22 may be but a few thousandths of an inch. The out-of-alignment movement of the ways 23 as to the openings 7, pinch the wire strands 3 at the corners of the openings 7. As the strands 3 are clear of the offset 8, the pressure release there prompts a bulking or enlarged thickness region for the strands 3. The second abrupt direction change for the strands 3, is against the opposite side to this loosening, as the pushing side of the ways 23 effect this locking operation on the wire strands 3.

Similarly to the centering feature for the plug 16 (Fig. 1) of the plug recess 90 to receive the projection 91, the plug 49 (Fig. 9) may be centered by projection sections 92 (Figs. 10, 11) to enter a seat 93 (Fig. 9). Along an analogous

line of construction, a projection 94 (Fig. 12) may enter a seat 95 in the rocker or plug 78. There is practical worth in these cooperating interfitting portions at the region intermediate the different strands approach to the rocker plugs. Should any stray wire strand miss the terminal opening, it may not readily be sufficiently astray to become associated across the central region of the rocker with the opposite or different electric current. Occasion for shorting or objectionable disturbance is thus avoided.

What is claimed and it is desired to secure by Letters Patent is:

1. An electric connector comprising an insulation housing having a terminal locating seat therein, there being a way to the seat for a conductor, a terminal in the seat having an offset provided with an opening through the offset in fixed register with the way for a conductor, and a movable insulation member in the housing having a way portion to receive a conductor extending thru the terminal offset opening, said member being shiftable in the housing relatively to the terminal offset thereby to lock the conductor extending thru the offset opening against removal from the terminal opening.

2. An electric connector insulation housing having therein from a common face, a central recess with opposite channel sides forming seats, a pair of terminals adapted to seat in the housing channel side seats with prong portions to extend therebeyond from the common face, and a relatively rotatable insulation plug adapted to be inserted in the housing recess thereby to fix the terminals in the seats to a locking position of assembly therefor with the housing, said housing away from said common face having conductor lead in way means, said terminals having offsets providing openings in register with the way means, and conductor leads thru the way means protruding thru the openings to be engaged by the plug in plug rotation relatively to the housing to grip said leads with the terminals.

3. An electric connector comprising an insulation housing having from a face thereof a recess with a pair of terminal-locating seats therealong, from a different face of the housing there being conductor directing way means to the seats, a terminal in each seat, said respective terminals each having an opening thru an offset and held by the seats into register with a conductor thru the way means, said conductors, and an insulation member in the recess having way means to register with the terminal offset openings to receive protruding end portions of the conductors, said member being shiftable in and relatively to the recess thereby to bend conductor protruding end portions against the offsets in locking the terminals with the conductors.

4. An electric connector comprising an insulation cylindrical housing having a conductor-directing opening from one end to a wedge guide and a plug member receiving recess from the other end, there being terminal-locating seats along the recess communicating with the conductor opening at opposite sides of the wedge guide, terminals in the seats having inner end offsets with openings in register with the conductor opening adjacent the guide, an insulation plug member in the recess having conductor-end-receiving openings adapted to abut and register with the offset openings, and a conductor pair insertable into the housing conductor-directing opening and spaced by the wedge to pass thru the offset openings and enter the member conductor-

end-receiving openings, said housing and member having coaction holding means against outward shifting of the member upon angular movement relatively to the housing-held terminals in thereby bending the conductor ends against the offsets of the terminals at the openings.

5. An electric connector comprising an insulation two-part housing having a terminal communication face at one side and a conductor-receiving opening at a different side, said latter opening extending to a wedge guide, the terminal communication face having a recess with terminal-locating seats along opposite sides thereof to communicate with the opening, terminals in the seats having perforated end offsets in proximity to the guide, a relatively rotatable insulation member seated in the recess and coacting to position the terminals in the housing, said member having conductor end receiving openings adapted to register with the terminal offset perforations, and a conductor pair insertable into the conductor-receiving opening and directed by the guide to have end portions pass thru the terminal perforations and enter the insulation member openings, whereby rotation of the member relatively to the housing effects pinch holding of the conductors with the terminals at the offsets.

6. An electric connector comprising an insulation housing with an exposed outer face and therefrom a central recess with its contour interrupted by way-providing channels forming seats having general direction away from said face, a

pair of terminals having portions complementary to and sufficiently in register with different spaced seats to leave portions of said terminals approximate closing of the channels in approaching conformity with the contour of said recess, said terminals having prong portions extending from said face, and an insulation plug insertable into said housing recess and there rotatable relatively to the housing and terminals to lock the terminals in fixed assembly with the housing and plug, said housing and plug having interfitting projection and recess portions coacting for ready detachment and reassembly.
